UNITED STATES PATENT OFFICE.

ARCHIE A. STEWART AND JOHN H. STEWART, OF WATERLOO, IOWA.

CENTRIFUGAL ROUNDABOUT.

Application filed October 11, 1926. Serial No. 140,826.

Our invention relates to improvements in centrifugal roundabouts, and the object of our improvements is to supply a device of this class of a simple construction and where-
5 in the centrifugally deflected carrier is rotated about the axis of the device by means of operating means mounted upon the carrier.

This object we have accomplished by the
10 means which are hereinafter described and claimed, and which are illustrated in the accompanying drawings, it being understood that various modifications may be made in the mechanisms of the device without de-
15 parting from the invention or the scope of our claims.

In said drawings, Fig. 1 is an elevation of said device, and Fig. 2 is an elevation there-
20 of looking toward its axis. Fig. 3 is a top plan view of the device, and Fig. 4 is an enlarged detail view of a portion of one of the horizontal radial arm members, showing the manner of mounting an end sheave there-
25 on with its angular relation to the pivotal connection of the carrier hangers.

The numeral 1 denotes a tubular metal axial standard whose lower end may be af-
fixed to a solid base. The numeral 7 de-
30 notes a slidable sleeve mounted upon said standard or axis 1 and releasably secured thereon by a set-screw 8 for vertical adjust-
ments. The numeral 3 denotes another sleeve mounted loosely upon the standard spaced vertically from the sleeve 7, and carries a
35 pair of spaced rigid horizontal and radial arm members 2 projecting away from the upper part of the standard to be rotated around it by mechanism to be described. From another sleeve 6 mounted loosely upon
40 the standard 1 and resting upon the ad-
justable sleeve 7 projects brace-bars 4 the members of which are inclined upwardly and bolted to the outer end parts of the members 2. A pair of struts 5 are bolted
45 to the members 2 and 4, extending verti-
cally, at their ends spaced in parallel from said standard. Immediately above the loose sleeve 3 a hub 9 is secured adjustably upon the standard 1 by means of a set-screw
50 10, and this hub carries a coaxial integral relatively large chain-gear sheave 11 which is thus adjustable vertically upon the stand-
ard, but is fixed thereto. It will be seen that by loosening the two set-screws 10 and
55 8, the arm 2 and said sheave 11 may be

shifted up or down the standard 1 to dif-
ferently adjusted positions.

The outer end parts 2' of the arm mem-
bers 2 are bent oppositely to thus provide
furcations inclined toward each other but
60 separated at their ends which are bent to
be parallel, with the parallel terminations
directed upwardly at an angle of 45 degrees
to the arms 2 and supplied with transversely
aligned holes 15 to seat a pivot-bolt on whose
65 medial part the upper apertured end of the
stem 16 of a T-body 17 is pivoted to swing
dependingly from or to said standard 1
under the influences of centrifugal force
or gravity respectively. As shown in Fig. 70
2, the oppositely directed parts 17 are ap-
pertured to seat the upper ends of a pair of
depending parallel tubular hangers 18 whose
upper ends are exteriorly threaded to seat
adjustable nuts 20 and 21 below and above
75 said parts 17 to permit of vertical adjust-
ments of the hangers. The lower ends of
the hanger tubes 18 are removably mounted
in threaded sleeves or sockets 22 fixed on
80 the horizontal part of a flat bar 23 whose
outer longer limb 24 is bent upwardly slop-
ingly. A seat 26 is adjustably mounted upon
said sloping bar part 24 by means of a
bolt 32 passed through any of longitudinally
aligned holes 31 in said bar, and secured by
85 a nut 25. From the horizontal part of the
bar 23 midway between the hangers 18 fix-
edly depends a forked member 27 whose fur-
cations are apertured in line to seat a short
90 horizontal shaft 28, radially directed from
said standard 1, and having fixed thereon
the hub of a chain-gear pinion 30 immedi-
ately below the hangers 18. The shaft 28
has oppositely disposed end cranks 29 whose
95 end members are located for pedaling.

The numeral 13 denotes like chain-gear
100 idlers mounted rotatably upon stud axes
14 (see Fig. 4) fixed upon the outer faces
of the inclined arm parts 2' so that the
idlers are set angularly upon the arm parts
105 with relation to each other. These idlers
have their said axes positioned a short dis-
tance inwardly upon the arm parts 2' rela-
tively to the pintle-bolt which is seated in
the apertures 15, and so spaced relatively to
110 said apertures 15 that the latter are alined
transversely with the chain 12 which is
seated in the circumferential grooves of
said idlers and which also passes around
the grooved peripheries of the pinion 30

and said fixed sheave 11. The idlers are at such an angle relative to the arm members 2, that the chain 12 runs from opposite sides of the fixed sheave 11 in line with the 5 grooves of the idlers. It should be particularly noted that the apertures 15 of the fur- cations 2' as shown in Fig. 4, are positioned at angles of 45 degrees from the axes of said idlers 13, so that being alined with the 10 chain parts transversely, the chain cannot ride out of the circumferential grooves of the idlers, no matter how much the hangers swing outwardly under the influence of cen- trifugal force toward a horizontal position. 15 If the pivotal connection 16 of these hang- ers is located elsewhere, the chain 12 will ride off of the idlers, so that this relative positioning of the hanger pivot bolt and the axes of the idlers is vital. 20 While this device is primarily designed for use by children yet it may be made of a suitable scale for adult use, and while only one arm 2 and carrier are shown, it is to be understood that one or more other arms 2 25 and depending carriers may be included in the combination without departing from this invention. The operator, when seated on the seat 26 may grasp the hangers 18 ahead for steadyng, and then by pedaling 30 the cranks 29 may rotate the chain-gear pinion 30 to drive the chain 12 which trav- erses the hollows of the tubular hangers. As the operator is seated above the bar 24— 35 23, and the pinion 30 is immediately below the latter, clothing cannot become entangled in the pinion and chain. It will be under- stood also, that the carrier with said arm 2 is revolved around the standard 1, by the engaging of the chain links upon the re- 40 cessed tread of the large fixed chain-sheave 11, and releasing therefrom around the sheave.

Having described our invention, what we 45 claim as new, and desire to secure by Letters Patent, is:

1. In a centrifugal roundabout, an arm 50 rotatable horizontally about a fixed axis, a carrier pivotally depending from said arm to swing to and from said axis, a sheave fixed upon said axis, a sheave rotatably mounted upon said carrier, idler sheaves ro- 55 tatably mounted upon said arm spaced in- wardly from the pivotal connection of said carrier with their treads transversely po- sitioned approximately in line with the pivotal connection at angles of approxi- mately 45 degrees from the axes of the idlers, and a flexible driving member mount- ed about said sheaves and said idlers. 60 2. In a centrifugal roundabout, an arm

rotatably and vertically adjustably mount- ed upon a fixed axis, a carrier pivotally mounted on the outer extremity of said arm to swing to and from said axis, a chain- gear sheave fixed upon said axis for verti- 65 cal adjustment relative thereto, a chain-gear sheave rotatably mounted upon said carrier having end cranks, idler chain-gear sheaves rotatably mounted upon opposite sides of said arm spaced inwardly from said carrier 70 pivotal connection with their axes below the level of said pivotal connection and at angles of approximately 45 degrees relative thereto, and a driving chain passed around said fixed and rotatable sheaves and about 75 said idler sheaves.

3. In a centrifugal roundabout, an axial standard, an arm mounted rotatably upon said standard for vertical adjustments thereon, a chain-gear sheave fixed adjust- 80 ably upon said standard immediately above said arm, chain-gear idlers rotatably mount- ed on opposite sides of said arm with their treads in line with the tread of said fixed sheave and their axes horizontal and in- clined toward said arm, said arm having a 85 termination inclined upwardly with a trans- verse pivot thereon, a hanger pivotally mounted on said pivot to swing outwardly from said standard under the influence of 90 centrifugal force, the pivot on said arm be- ing positioned at an angle to the axes of said idlers and between the treads thereof substantially at their pitch-circles, a chain- gear sheave rotatably mounted on the low- 95 er part of the hanger and having oppo- sitely directed end cranks, a seat support fixed upon said hanger, a seat adjustably mounted upon said seat support, and a driv- 100 ing chain passed about said fixed and ro- tatable sheaves and said idlers.

4. In combination, a fixed sprocket-wheel, an arm rotatable around the axis thereof, a pair of sprocket-pinions mounted on oblique axes upon said arm, a carrier sus- 105 pended on the arm to swing outwardly, the treads of said pinions positioned approxi- mately in line with the pivotal connection of said carrier with said pivotal 110 connection at angles of approximately 45 degrees from the axes of said pinions, a shaft having end pedals and carrying a driving sprocket-wheel and rotatably mount- ed on the carrier, and a chain engaging said 115 wheels and pinions.

In testimony whereof we affix our signatures.

ARCHIE A. STEWART.
JOHN H. STEWART.
